UNITED STATES PATENT OFFICE.

FRANCIS J. McCLISH, OF ST. LOUIS, MISSOURI.

DESIGN FOR AN IMAGE.

Application filed February 5, 1925. Serial No. 12,270. Term of patent 3½ years.

To all whom it may concern:

Be it known that I, FRANCIS J. McCLISH, a citizen of the United States, residing at the city of St. Louis and State of Missouri, have invented a new, original, and ornamental Design for an Image, of which the following is a specification, reference being had to the accompanying drawing, forming part thereof.

In the drawing Fig. 1 is a top plan view of the image.

Fig. 2 is a front view.

Fig. 3 is a side elevation.

Fig. 4 is a rear elevation.

I claim:

The ornamental design for an image, as shown.

FRANCIS J. McCLISH.
